BOILER FURNACE CONSTRUCTION

Application filed April 19, 1930. Serial No. 445,611.

These improvements relate to the protection of furnace walls which are exposed to the products of combustion of liquid or solid fuel, and particularly powdered coal. The drawings relate to the detailed construction of one type of boiler furnace embodying my invention.

In the utilization of powdered coal there has been a greatly increased tendency towards very rapid rates of combustion. Although there are a number of factors which may determine the limit to which the rate of combustion may be increased, the present practical limit in the case of boiler furnaces is determined by the rate of deterioration of the refractory used as a lining for the combustion chamber.

The breakdown of the furnace lining is due primarily to the action of the molten coal ash or slag which accumulates on the walls of the furnace. The principal problem therefore is the regulation of the wall temperature to such a degree that the slag in contact with the refractory is no longer sufficiently fluid to have a severe erosive or fluxing action on the furnace wall. This regulation is the cause of considerable difficulty, and many expedients have been tried in an effort to produce the desired effect. Both air and water cooling have been attempted, but when fireclay refractories are used the thermal conductivity of the wall is so low and the thickness necessary for mechanical strength at high temperatures so great that cooling by this means is ineffective.

In a copending application of Clarence E. Hawke, Serial No. 244,734, filed January 5, 1928, now United States Patent No. 1,828,839, patented October 27, 1931, a boiler furnace is disclosed in which the difficulty of regulating the wall temperature is overcome to a great extent by the use of an air cooled refractory lining of silicon carbide. The latter combines strength at high temperatures with exceptionally high thermal conductivity, so that a section may be employed which is highly conductive. The walls are cooled by the passage of air through ducts

chamber, and the air thus pre-heated is introduced into the furnace and utilized for combustion. Owing to the fact that it is possible to use a thin wall of high conductivity, the cooling effect can be increased to 55 as much as twenty times that obtained with fire clay.

In addition, the amount of cooling has been found to be much more nearly proportional to the velocity of the air circulated through the wall than when fireclay refractories are used, and it becomes possible to regulate the temperature of the wall within certain limits by a variation in the velocity of the circulating air. As an example, when the furnace temperature is approximately 1300° C., the amount of heat extracted from a two and one-half inch silicon carbide wall can be increased from 15000 to 28000 B. t. u. per square foot per hour by increasing the 70 velocity of the air from 10 to 50 feet per second.

In order to obtain effective regulation of the wall temperature by air cooling, the thermal conductivity of the refractory lining 75 must be greater than .006 cal/cm²/sec./°C. The thermal conductivity of silicon carbide refractories varies with the material used as a bond, but with refractories composed principally of silicon carbide the conductivity is 80 usually between .02 and .04 cal/cm²/sec./°C., and may be slightly higher. Even when thirty per cent clay is incorporated into the mix, a conductivity of .014 cal/cm²/sec./°C. may still be attained. The thermal conductivity of self-bonded silicon carbide is approximately .05 cal/cm²/sec./°C. By "silicon carbide refractory" is meant a refractory composed principally of silicon carbide, even though it may contain other materials or 90 bonding agents.

In boiler furnaces operating at very high ratings, it is not always possible or practical to cool the walls to the desired temperature by air alone, even when silicon carbide is 95 used. Obviously, if the efficiency of the furnace is to be preserved, the heat absorbed by the air in cooling the walls must be re-introduced into the furnace, and when the latter is operated at high ratings the volume of air 100

necessary for the cooling of all four walls may be so great that its introduction into the combustion chamber is impractical.

The alternative of using less air and heating it to a higher temperature is also undesirable, for when this is done the efficiency of the cooling is greatly decreased. Under these conditions the circulating air produces much less cooling, not only because of its higher temperature, but also because of the limited velocity necessary when less air is used. The latter factor eliminates to a large extent the possibility of regulating the wall temperature by a variation in the velocity of the air, which is one of the chief advantages derived from the use of an air-cooled silicon carbide wall structure. In addition, if the air is preheated to extreme temperatures it cannot be passed through the burner without danger of injuring the steel and making the fuel sticky.

In the present invention I have effected a combination of air-cooled and water-cooled silicon carbide walls which permits exceptionally high combustion ratings without damage to the refractory lining, and at the same time retains the advantage of temperature regulation afforded by air cooling. In carrying out this invention, I employ a boiler furnace in which one or more walls are composed of silicon carbide blocks surrounding a water cooling medium which may be directly connected to the boiler circulating system. The necessary cooling of the furnace walls in excess of that which can be furnished by the amount of air used in combustion is provided by this means. In the remaining walls a silicon carbide structure is employed wherein cooling is effected by the passage of air through ducts in or behind the wall. The air pre-heated by circulation through the wall is introduced into the furnace, and the preheating is sufficient to increase the rate of combustion by affording practically instantaneous combustion of the particles of fuel.

The air circulated through the walls may be introduced directly into the burner or into the combustion chamber through suitably located apertures or ports in the wall itself. There are certain advantages, however, in the latter procedure. Instead of the flame or the hot products of combustion coming in direct contact with the wall, the air issuing into the furnace through the wall affords a protective envelope which produces the same effect as would additional cooling in the case of the solid wall. In addition to the cooling effect of this envelope of air, an oxidizing atmosphere is also provided at the surface of the refractory, and the melting point of the slag is thereby considerably raised. The erosive action of the slag is principally due to the formation of a low-melting ferrous silicate, and if conditions are

such that the iron of the coal ash is oxidized to a higher state, the erosion at a given wall temperature may be considerably lessened.

The combination of air-cooled and water-cooled silicon carbide walls makes possible a regulation of wall temperature which cannot be obtained by the use of either method of cooling alone, or by a combination of both methods in conjunction with the usual poorly conducting refractories. When silicon carbide walls are cooled entirely by water, the rate of cooling is practically predetermined, and regulation cannot readily be effected to correspond with the heat generated in the furnace. If the temperature gradient in the wall is such that it will withstand high ratings, the cooling produced at any rating appreciably below the maximum is so great that the air in the vicinity of the wall is chilled to the point where it will not support rapid or instantaneous combustion.

There is therefore a tendency for a certain proportion of the fuel to pass unburned into the tube passes and thence into the stack. Although regulation can be obtained with air-cooling alone, the amount of cooling, as previously pointed out, is so limited that protection cannot be economically obtained at high rates of combustion. By embodying one or more water-cooled silicon carbide walls in a furnace employing air-cooling in conjunction with a silicon carbide refractory, the hotter air-cooled wall imparts its heat by convection, conduction and radiation to the water-cooled wall until the temperature differences are considerably reduced superficially, and the regulation of wall temperature at high ratings is just as effective as when air-cooling alone is used at a somewhat lower rating. Combustion can also be maintained efficiently at lower ratings than would be possible if air-cooling were not used. The fact that pre-heated air is available to accelerate and support combustion offers an additional advantage in that the loss of unburned fuel which would otherwise take place with water-cooled side walls at low rates of combustion is greatly reduced.

An example showing a type of construction which may be employed in carrying out my invention is illustrated in the accompanying drawings.

Figure 1 represents a vertical section through a powdered coal boiler furnace in a plane at right angles to the axis of the boiler itself and parallel to the water-cooled walls;

Figure 2 shows a section at right angles to that of Figure 1 along the section line A—A of Figure 1 parallel to the air-cooled walls;

Figure 3 is a fragmentary section on the line 3—3 of Fig. 1; and Figure 4 is a fragmentary section on the line 4—4 of Figure 3.

Referring to the drawings in more detail, 2 designates generally a furnace for heating a boiler 3, the boiler having tubes 4. Two

walls of the furnace 5 and 6 are provided with a lining of a silicon carbide refractory within which are air-circulating passages or ducts 7 and 8, respectively. It will be noted that in the wall 6 one set of ducts 8 is located above the other set of ducts 8, the upper and lower ducts being separated by a partition 9. A blower 10 is provided for circulating air through these ducts or passages, the air from the blower being delivered to pipes 11 and 12. The pipes 11 communicate with the bottoms of the ducts 8 while the pipe 12 discharges air into the top of the ducts 7. A damper 13 is provided in each of the pipes 11 and 12 for regulating the flow of air therethrough. In this particular type of construction, the air is introduced into the combustion through ports 14 at the ends of the ducts 7, and ports 15 at the ends of the ducts 8, these ports being distributed in such manner as to procure the most effective cooling action of the air circulating through the ducts.

The other two walls 16 are of similar construction, being faced with a silicon carbide refractory and having water-cooled walls, the water being transmitted through pipes 17 embedded in the walls. These pipes are preferably connected directly to the boiler system by means of headers 18 and 19, and the rate of flow may be controlled by means of suitable valves. Some of the water in the pipes 17 may be vaporized owing to the high thermal conductivity of the silicon carbide walls and the thin layer of refractory 16 shown, for example, in Figure 2.

While the inner face of the walls is comprised of a silicon carbide refractory, the portion of the walls outside the ducts 7 and 8 and outside the pipes 17 is composed of a refractory material having a comparatively low thermal conductivity, such as fire clay, and which may be covered with suitable insulation, as indicated.

A blower 20 is indicated at the right of Figure 1 for discharging powdered coal through pipes 21 to the outlets or burners 22 at the top of the furnace.

The character of the burner orifice 21 is shown in Figure 3 and in Figure 4. The burner orifice is flattened out and extended in a direction at right angles to the plane of Figure 1 so as to produce a sheet of flame at right angles to the water-cooled walls and therefore at right angles to the plane of the pipes 17 shown in Figure 1.

In the design of boiler furnaces the burner is often constructed so as to afford a sheet of flame extending over practically the entire width of the furnace, and parallel to one of the furnace walls, or in the case of a square furnace, parallel to two opposite walls. In determining the location of the apertures 14 and 15 for the introduction of air into the furnace, I prefer to introduce the air through

the walls which are parallel to the initial direction of the sheet of flame and in such a manner that the flame is blown away from the walls. The air is thus introduced at an angle to the sheet of flame rather than in a direction parallel to it.

Other types of burner than that shown in the drawings may be used. For example, one or more horizontal burners may be used as an alternative for the type of burner shown. In this case the fuel is introduced through one or more ports in the side wall instead of through the top portion of the furnace. If more than one burner is used, it is desirable to adjust the burners at such an angle with respect to each other that a swirling motion will be imparted to the flame.

By combining the use of air-cooled silicon carbide walls with that of water-cooled walls of like material to give additional cooling over the maximum amount obtainable with the volume of air used for combustion, I have found that the walls may be protected to a high degree even when very high flame temperatures are reached and that the efficiency of the furnace is not impaired by the cooling so produced.

The amount of air employed for combustion increases as the rate of combustion increases, since with silicon carbide the cooling effect is greatly increased by increasing the velocity of the circulating air (which is not the case with fire clay and the refractories previously employed), it is thus possible within certain limits to maintain a practically constant wall temperature even with increased rates of combustion. The air flow and the corresponding rate of cooling may be regulated to correspond with the rate of heat generation within the furnace. By confining this action to only a portion of the wall surface, as for example two walls instead of four, the limits through which this regulation of the wall temperature may be maintained are greatly increased. The rate of air circulation may be varied by varying the speed of the blower 10 as well as by adjustment of the dampers 13.

In the operation of the furnace the refractory wall is protected by a thin layer of solidified slag. The slag itself is a poor thermal conductor, and even when a fairly thin layer has congealed on the furnace wall, the temperature gradient may be so great that additional slag will no longer solidify but will run down the walls of the furnace. This represents an ideal condition for the protection of the refractory lining, and is one which may be readily realized by the wall structure here described. By regulating the velocity of the air or the relative ratio of the amount of air circulating through the walls compared with that directly entering the burner, the wall temperature may be so regulated that the layer of solidi-

fied slag is sufficient for protection and yet remains comparatively thin, the remainder of the slag in contact with the wall being sufficiently fluid to permit its ready removal from the bottom of the furnace.

In certain types of furnaces the area of the wall face subjected to excessive temperatures is only a portion of that making up the combustion chamber. In such a case it is desirable to cool the portion of the wall subjected to extreme conditions to a greater extent than the portions further removed from the fire zone. In order to secure the advantages of the air-cooled and water-cooled silicon carbide structure described herein, the portion of the furnace subjected to extreme flame temperature may be composed of silicon carbide, one or more walls being air-cooled and the remainder being water-cooled, and the more remote portions of the wall or combustion chamber made from the usual materials such as fireclay.

I claim as my invention:

1. A boiler furnace for burning powdered coal fuel at high rates of combustion and for operating the boiler at correspondingly high ratings comprising in combination a combustion chamber having front, back and side walls with silicon carbide linings for the exposed surfaces of said chamber; a burner arranged to project a sheet of flame downward from an opening in the top of the chamber so that said sheet is initially parallel to the front and back walls, air ducts in one said of said walls for pre-heating air by transmission of heat from the upper portion of said sheet of flame, air inlets for the air ducts whereby the air thus preheated is admitted to the combustion chamber, another series of air ducts in the same wall for pre-heating air by transmission from the lower portion of the flame and delivering said air at an intermediate level in the combustion chamber, a third series of air ducts arranged in the wall opposite to the burner outlet and arranged to deliver preheated air to the lowermost portion of the combustion chamber, boiler tubes extending across the outlet of the combustion chamber above said last-mentioned air-cooled wall, other boiler tubes embedded in the side walls and extending substantially the length thereof, and means for varying the respective rates of air and water cooling.
2. A boiler furnace adapted for burning powdered coal comprising in combination a combustion chamber having front, back and side walls each consisting of a thick outer wall of poorly conducting refractory and a thin inner lining of highly conducting refractory adjacent the combustion chamber, a burner projecting through the roof of the combustion chamber and having a slit-shaped orifice for the discharge of fuel in a downward direction initially adjacent and parallel to

said front wall, air ducts in said front wall in contact with the highly conducting refractory and having inlets for cold air and outlets for the same air after it has been heated by transmission from the downwardly projected flame, other air ducts in the back wall having inlets for cold air and outlets adjacent the base of the flame, and boiler tubes in the side walls in contact with the highly conducting lining.

In testimony whereof I have hereunto set my hand.

HENRY P. KIRCHNER.
